UNITED STATES PATENT OFFICE.

ROBINSON BURT, OF BUFFALO, NEW YORK, ASSIGNOR TO F. N. BURT COMPANY, LIMITED
OF BUFFALO, NEW YORK, A CORPORATION OF ONTARIO, CANADA.

LABELING-MACHINE.

1,180,005.

Specification of Letters Patent. Patented Apr. 18, 1916.

Application filed July 10, 1913. Serial No. 778,255.

To all whom it may concern:

Be it known that I, ROBINSON BURT, a citizen of the United States, residing at Buffalo, in the county of Erie and State of New York, have invented certain new and useful Improvements in Labeling-Machines, of which the following is a full, clear, and exact description, such as will enable others skilled in the art to which it appertains to make and use the same.

This invention relates to labeling machines, and with respect to its more specific features to machines of the character referred to involving apparatus for folding flexible labels on boxes and adhesively securing the same thereto.

One of the objects of the invention is the provision of a practical device for automatically adhesively attaching paper labels or strips to boxes.

Another object of the invention is the provision of an efficient mechanism for adhesively attaching and folding labels or strips around sectional boxes, such as the small, relatively stiff paper boxes ordinarily employed for containing cigarettes, the parts of said box comprising a base and a cover.

Another object of the invention is the provision of practical and efficient mechanism for adhesively attaching labels or strips to boxes and causing said labels to present a smooth and neat appearance.

Still another object of the invention is to apply a strip or label to a sectional box across the joint thereof and securely adhesively affix the same thereto in order that it will serve as a hinge for the cover and base.

Still another object is the provision of efficient mechanism for applying labels to boxes in accurate, predetermined position relative thereto, and to accomplish such result upon a plurality of boxes in a rapid manner.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings forming a part of this specification and in which

similar reference characters refer to similar parts throughout the several views, Figure 1 represents a front elevation of a labeling machine, showing the preferred embodiment of the invention; Fig. 2 represents a rear elevation of said machine; Fig. 3 represents a side elevation of the machine from the right; Fig. 4 represents a side elevation of the machine from the left; Fig. 5 is a detail plan view of the label mechanism; Fig. 6 is a vertical section of Fig. 5 on the line *a—a*; Fig. 7 is a detail sectional view on the line *b—b* of Fig. 5; Fig. 8 is an enlarged rear elevation of the glue reservoir and the adhesive or glue-applying devices; Fig. 9 is a sectional view of Fig. 8 on the line *c—c*; Fig. 10 is a detail sectional view of Fig. 8 on the line *d—d*; Fig. 11 is an enlarged plan view, partly in section, of the box supply device; Fig. 12 is a detail view of the device for operating the primary box pusher; Fig. 13 illustrates the cam operating means of the device shown in Fig. 12; Fig. 14 is a detail sectional view, showing the yielding joint in a primary box pusher rod; Fig. 15 is a longitudinal sectional elevation of the reciprocatory box carrier; Figs. 16, 17 and 18 are detail views of parts of the reciprocatory box carrier; Fig. 19 is a side elevation, partly in section, showing the endless belt box carrier and the cam operating mechanism of the reciprocatory box carrier; Fig. 20 is a sectional view, showing the disposition of the endless belt relative to the box supply supporting device; Fig. 21 is an enlarged view of the upper and lower rotary carriers and adjacent parts, viewed from the left-hand side of the machine; Fig. 22 is a detail of a part of Fig. 21; Fig. 23 is an enlarged view of the upper and lower rotary carriers and adjacent parts, taken from the right-hand side of the machine; Fig. 24 is a view of the cam device for operating the oscillatory plate of the lower carrier; Fig. 25 is an enlarged front elevation of the upper and lower rotary carriers, partly in section in order to more clearly disclose certain details; Figs. 26 and 27 are detail views of portions of the upper and lower carriers, respectively; Fig. 28 is an end elevation, partly in section, showing the arrangement of the devices for folding the ends of the label over each other on to the box; Fig. 29 is a plan view, partly in section, of one of

the end folding devices and its operating part; Fig. 30 is a side view of the cam operating mechanism of the device illustrated in Fig. 29; Fig. 31 is a section of Fig. 28 on the line *c-c*; Fig. 32 is a section of Fig. 29 on the line *f-f*; Fig. 33 is a plan view of the rear end of the machine, showing the arrangement of the slitting mechanism and its operating parts; Fig. 34 is a side sectional elevation of Fig. 33; Fig. 35 is a sectional view, illustrating the arrangement of a box-retaining dog employed, associated with the slitting mechanism; Fig. 36 is a rear elevation of the slitting mechanism; and Fig. 37 is a plan view, partly in section, showing the lower carrier, the slitting mechanism and the press through which the labeled boxes are conducted from the lower carrier to the slitting guideway.

Machine frame.—Before referring to the several operating devices of the present embodiment of this invention and to the details thereof, the construction of the supporting parts of the machine will be set forth. The operating parts of the machine are carried by a table comprising a top 1, and legs 2, the latter being connected by a brace rod 3. Upon the base frame, formed by the aforesaid parts, is supported an upper frame consisting of upright spaced castings 4 and 5 bolted at each side of the table, the upper ends of said castings being rigidly connected by a cross-piece 6. The castings 4 and 5 have rearwardly extending heavy bracket portions 7 and 8. Other parts of the supporting frame will be referred to as the description progresses.

General driving mechanism.—Supported in bearing blocks 9 and slightly above the table top is a main driving shaft 10 extending transversely of the machine at the rear portion thereof, said main shaft having a belt pulley 11 loosely journaled thereon at the right side of the frame and provided with one element 12 of a friction clutch. A co-operative clutch element 13 is splined on the main driving shaft so as to be rotated thereby but having longitudinal movement thereon. Said element 13 carries a grooved collar 14, the groove of which is engaged by a fork 15 of a sliding shift rod 16, which latter passes beneath the machine to the left side of the frame and is pivotally connected to an arm 17 of a rock shaft 18, the latter at the front of the machine being provided with a hand lever 19 adapted to co-operate with a latch 20 to retain the hand lever in its outer position and thereby retain the clutch elements 12 and 13 in engagement. Motion is communicated to the several moving parts of the machine from the main driving shaft 10.

Label supply device or magazine.—In the present embodiment the labels or strips to be assembled with the boxes have a general

rectangular outline and a pack of such labels is held in a magazine in proper position to co-operate with other operative parts of the machine as will hereinafter appear. The label supply device or magazine is located at the upper portion of the machine and preferably is supported by the cross-piece 6. Said cross-piece may be of an increased width centrally, as illustrated, and is provided with a rectangular centrally disposed opening 21. The upper face of the cross-piece around said opening is flat and slidably mounted thereon is a label finger supporting plate 22 having a central opening 23 opposite the opening 21 in the cross-piece, the plate 22 having tongues 24 on its bottom engaging grooves 25 on the top of the cross-piece 6, said grooves 25 extending transversely of the machine. The tongue groove arrangement permits the finger supporting plate 22 to be moved transversely of the machine and serves to guide such movement. Said transverse movement of the plate 22 is accomplished by means of a shaft 26 having threaded engagement with a lug 27 on the cross-piece and provided at one end with a hand wheel 28. The shaft 26 has a swiveled connection with the plate 22. In order to prevent a too free movement of the plate 22 the same is spring-pressed against the cross-piece preferably by springs 29, surrounding pins 30 projecting from the cross-piece and through slots 31 in the plate 22. A nut 32 serves to adjust the tension of said springs. By this construction the label supply device or magazine may be fixed opposite a predetermined point of the path of certain label carrying plates 136 hereinafter referred to; that is, it will have no automatic movement in a plane parallel to the movement of the label carrying surfaces of the carriers 138, although it is within the purview of this invention to permit the magazine to move toward and from the path of said carrier plates. The plate 22 carries the devices which directly support the pack of labels. To this end, rigid plates 33, having angularly disposed arms 34, are adjustably connected to the plate 22 by means of a screw-bolt 35 passing through slots 36 in the plate 33. Beneath each plate 33 is a similar plate 37 having a downwardly projecting arm 38 provided at its lower portion with an adjusting screw 39. For convenience of mounting, the plates 33 and 37 are so located that the pins 30 pass therethrough, the springs 29 resting upon the plate 33. Bolted to arms 34 are label supporting fingers 40, preferably of resilient metal, the lower ends of said fingers being provided with inwardly extending flanges 41, the fingers 40 tapering downwardly thereby providing small ends to support the pack of labels. The adjusting screws 39 serve to move the lower ends of the fingers 40 so that

they may be accurately positioned in accordance with the size of the label to be supported. In the present embodiment where in the sides of the label are unequal in 5 length, a pair of fingers is disposed at each side of the longer side of the labels, one finger being sufficient at each side of the shorter side of said labels. The cross-piece 6 may be provided with a scale 42 and the plate 22 10 with an indicator 43, if desired.

Adhesive supply device.—The bracket portions 7 and 8 of the castings provide horizontal upper faces on which is secured a platform 44. A tank or pot 45 rests upon 15 the platform 44 and is adapted to contain a suitable adhesive, such as glue. Rotatably mounted and so as to dip into the glue in the tank, is a relatively large glue supplying roller 46 contacting with a glue delivery 20 roller 47 journaled in brackets on the sides of the tank, said rollers being so mounted as to provide for an efficient transfer of glue from the tank to the delivery roller 47. As illustrated, the delivery roller is jour- 25 naled in spring-pressed boxes in the brackets.

48 represents a roller which may be adjusted relative to the roller 46 by means of the screws 49 so as to gage the thickness of the glue supplied to the delivery roller 47. 30 Spaced standards 50 are disposed adjacent and to one side of the roller 46 and each standard is provided with a vertically arranged guideway or slot 51 engaged by the sides of the reciprocatory frame 52 in the 35 lower portion of which is journaled a glue transfer roller 53. The parts are so disposed that when the frame 52 reciprocates the roller 53 will move into and out of contact with the roller 47, the latter yielding slightly 40 to the contact of the roller 53, and the movement of the applying roller 53 is accomplished through the instrumentality of a shaft 54 journaled in bearings on the standards 50 and provided near each end with 45 pinions 55 engaging racks 56 fixed to the frame 52. At one side of the shaft 54 is secured a gear 57 in mesh with teeth 58 of an adjustable rod 59 which latter is caused to reciprocate by a cam groove 60 engaging a 50 roller 61 mounted on the rod 59. The cam groove 60 is formed in a disk 62 secured to a countershaft 63.

As will hereinafter appear, the glue received by the roller 53 will be transferred to 55 a glue roller with which said roller 53 will make rolling contact and in order to uniformly apply glue to the carrier the transfer roller 53 is provided with a friction disk 64 adapted to contact with a friction plate 65. By this construction the direction of rotation of the roller 53 is controlled so that it will either be at rest or will be rotating in the direction in which it would rotate when applying glue to the carrier when 60 initially contacting with the carrier. The

roller 46 is sleeved to the shaft 66 and is provided with a clutch element 67 adapted to coöperate with the clutch element 68 splined on the shaft 66, and to the end of the shaft 66 is secured a sprocket wheel 69 70 which may be continuously driven by means of the sprocket chain 70 and a sprocket 71 on the main shaft 10. By manipulating the clutch element 68 the rollers 46, 47 and 48 75 may be thrown out of operation when desired. Each of these rollers is driven from the roller 46 by gears 72, 73 and 74.

The box or article supply device.—In the present embodiment it is designed to successively deliver labels from the label magazine and assemble them with boxes and preferably with small boxes comprising a cover and a base, such as a cigarette box, and it will be convenient at this point to disclose some of the details of the box supply device. 80 The box supply device is located at the front of the machine slightly above the table top where it may be conveniently reached.

The numeral 75 indicates an inclined frame-piece at one side of the longitudinal 85 central portion of the machine, one end of said piece being fastened closely adjacent the upper surface of the table top by a bracket 76, a standard 77 assisting in the support of said frame-piece. Pulleys 78 adjustably mounted at each end of the piece 75 serve to carry an endless conveyer belt 79, the upper plier of which rests on the frame-piece between upstanding box-guiding flanges 80. Said flanges terminate short of 90 the end of the belt supporting part of said frame-piece and at this point is a laterally projecting supporting plate 81 extending toward the longitudinal central line of the machine. 100

82 represents a transversely disposed guide block having an undercut groove engaged by a dovetailed tongue on a transversely reciprocating block or box pusher 83. As the boxes are fed by the endless carrier, the lowermost box assumes position opposite the pusher 83, an inclined plate 84 being disposed to keep the boxes down. The outer face of the endmost box rests against a shoulder 85 of the pusher block 83 and it will be 110 apparent that transverse movement of the pusher block will serve to move the endmost box from the carrier. The block 83 is of sufficient length to prevent the succeeding boxes from further forward movement until 115 it shall have returned to initial feeding position. The feeding movement of the pusher 83 is accomplished by means of a connecting rod 86 pivotally connected to the block 83 and to an arm 87 of a short rock shaft 88, 120 the latter being provided with a pinion 89 engaged by a rack 90 in turn reciprocated by a face cam 91 on a transverse shaft 92 supported in the bearings beneath the table top 1. The shaft 92 is continuously driven 125

through the instrumentality of a sprocket wheel 93 connected thereto, a chain 94 engaging the sprocket wheel 93, and a sprocket wheel 95 on the countershaft 63, said countershaft being properly supported in bearings on the bracket portions of the castings 4 and 5. The counter shaft 63 carries a large pinion 96 meshing with a small gear wheel 97 on the main driving shaft 10. The operative face of pusher block 83 is designed not to be quite as wide as the boxes so as not to chafe the succeeding box. The belt-pulley 78 is continuously driven from shaft 92 by sprocket and chain 78', 79'.

15 The connecting rod 86 is provided with a yielding joint so that the tension on the pusher 83 may be relieved under certain circumstances. Preferably said joint is comprised in a sleeve 98 to which the rock-arm 20 87 is pivoted, said sleeve encircling the connecting rod and being yieldingly held from longitudinal movement thereon by a spring-pressed pin 99.

Reciprocatory box support or carrier.—

25 Centrally of the table 1 is a post 100 provided with a longitudinally extending horizontal bearing in which slides a reciprocatory supporting rod 101, rectangular in cross section, having a vertically disposed head 30 102, the latter provided with upper and lower stationary jaws 103. Pivoted in front of the head 102 are upper and lower clamping members 104 having beveled flanges 105 between which the box to be labeled is 35 adapted to be gripped. The flanges 105 are preferably beveled, as illustrated in Fig. 16, so as to provide an intermediate flat face 106 adapted to contact only a small portion of the central part of the box and so as to avoid 40 friction between the box and the carrier, as far as possible, upon withdrawal of carrier, which friction tends to separate the box sections. The jaws 104 are yieldingly held from outward movement by means of 45 springs 107 surrounding pins 108 secured to the stationary jaws 103, nuts 109 being employed to adjust the tension of the springs. It will be perceived that the jaws 104 provide a transverse opening for the reception 50 of boxes delivered thereto by the pusher 83, and the head 102 assumes position at one side of the magazine such that the pusher will deliver a box from the magazine along the plate 81 and between said jaws, and 55 preferably the box might project longitudinally slightly beyond the ends of said jaws. Having been received by said carrier jaws 104, the jaws are moved forwardly in order to assemble a box carried thereby with a 60 label, as will hereinafter appear, whereupon the jaws retreat, leaving the box in contact with the label. In order to accomplish the reciprocation of the box-carrying jaws one end of a rock lever 110 fulcrumed on a 65 bracket 111 on the table is joined to the sup-

porting rod 101 by a connecting rod 112, the opposite end of the rock lever being operated through the instrumentality of a rod 113 provided with a roller 114 running in a cam groove 115 of a cam disk 116 on the 70 shaft 92.

In order to assure the delivery or ejection of the box from the gripping jaws 104 when brought to label-assembling position there is provided a box detaining rod 117 concentrically passing through the supporting rod 101 and having a portion 118 projecting beyond the front end of the supporting rod. The detaining rod is provided with a stop or pin 119, between which and an inner 80 shoulder of the supporting rod is located a spring 120 which exerts its force to draw the rod 117 in a direction to place its rear end 121 flush with the rear face of the head 102. Pivots mounted on top of the post 85 100 is a pawl comprising spaced parallel rods 122 having a hook or catch portion 123 and a cam or inclined portion 124. Passing between the rods 122 and secured to the post 100 is a pin 125 provided with adjustable stops 126, between which latter and said pawl is disposed a spring 127 adapted to move the pawl in a direction to cause a hook 123 to assume position in the path of the detaining rod 118. The cam 124 is so 90 disposed that the front end of the supporting rod 101 will contact therewith when in its forward position. By this construction it will be noted that when the head has been moved to transfer a box to the position occupied by the label to be assembled therewith the rod 117 will move with the rod 101 and the pawl 122 will be depressed so as to place the catch 123 in front of the end 118 of the detainer rod. Upon the retreat of the 95 supporting rod 101 said catch 123 will temporarily prevent the retreat of the detainer and the consequent relative movement of the jaws 104 and the detainer rod 117 will cause the box to be then held from movement 100 with the retreat of the box carrier. The 105 retreating supporting rod 101 will contact the incline 124 and lift the pawl 122 out of the path of the rod 118, thus permitting the spring 120 to retract the detainer rod 117, 110 whereupon it will again assume position for 115 ejecting the next box upon the next subsequent operation. In order to provide for accurate adjustment of the time when the catch 123 shall engage the rod 118 the front 120 end of said rod may comprise an adjustable threaded extension, as 128, and in order to similarly provide for the instant when the rod 117 is freed, the supporting rod 101 is provided with a contact member or sleeve 125 threaded thereon and adapted to contact with the incline 124 of the pawl 122. In line with the movement of the boxes when being transferred from the magazine to the reciprocatory box carrier is an adjustable 130

stop comprising a set screw 130 threaded in a bracket 131 projecting from the post 100. The stop prevents overthrow of the boxes and assists in alining them with the label carrier hereinafter referred to.

- 5 *The rotary carriers.*—Intermediate mechanism is provided for bringing together the labels from the label supply and the boxes successively delivered from the box magazine, and in the present embodiment portions of the intermediate mechanism are utilized in the accomplishment of accessory labeling operations distinct from the mere juxtaposing of said articles, to the end that 10 in the time consumed in the bringing together of said articles, one of them may be specifically prepared for assembly with the other. Supported in the frame castings 4 and 5, are two parallel transverse carrier 15 shafts 132 and 133, one below the other. At about the longitudinal central portion of the first or upper carrier shaft are fixed four supporting and guiding arms 134 diametrically disposed in pairs, and radially movable 20 on each arm, respectively, is a carrier arm or support 135 to the outer end of which is bolted or secured in any other approved manner a label carrier in the form of a transversely extending plate or block 136, the 25 outer surface of which is adapted to serve as a combined label support and label gluing pad. To this end, the outer face of the block 136 is preferably flat and is covered with material adapted to retain glue thereon and 30 transfer the same to a label strip applied thereagainst, and in the present instance a canvas covered rubber block 137 is employed. The block 136 has a recess 138 at about its central portion within which may play a 35 label stripping plunger comprising a head 139 at the end of guiding pins 140, one of which latter is surrounded by a spring 141 between the block 136 and a collar 142 on the pin, said spring serving to return the head 40 139 into the recess. The outer face of the head 139 when in its retracted position may 45 be disposed slightly below the outer surface of the pad 137 so that when said pad is being coated with glue, the glue will not be 50 applied to said head. Certain combined label stripping gripper arms operate in the path of the carriers, as will hereinafter appear, and in order to provide for the unobstructed movement of said arms the block 55 136 is provided at either side with ways or recesses 143 intersecting its outer face, the pad 137 being similarly recessed opposite the recesses 143. It will be understood that 60 each of the four label carriers above described are similar in construction.
- To the second or lower carrier shaft are fixed four carrier supporting arms 144 similarly diametrically disposed in pairs as those of the upper carrier and the outer end of 65 these arms terminate in transversely dis-
- posed label supporting faces or carriers 145 having intermediate openings or recesses 146 and in each recess are oppositely disposed transversely projecting folders or brushes 147. With each of the carriers on the shaft 70 133 is associated a pair of jaws 148 slidably supported on the carrier and adapted to move radially toward and from the surface 145 thereof. Each of said jaws 148 is provided with a beveled edge or finger 149 75 which co-operates with a similarly shaped groove in the face 145, and said jaws are located respectively in the rotary plane of the recesses 143 of the other carriers.
- The numerals 150 indicate brackets connected to the different arms of the lower carrier and journaled in said brackets are transverse rock-shafts 151 each having a pair of parallel arms 152 connected to the respective jaws 148 by universal joints 153 and 80 each shaft also having an arm 154 provided with a roller 155 cooperating with a cam edge 156 of a disk 157 journaled to oscillate on the shaft 133. Oscillatory motion is communicated to the cam disk 157 by means 85 of a rod 158 provided with a roller 159 engaging a cam groove 160 in a cam disk 161 on the counter-shaft 63. The contour of the cam 156 is such that the jaws 148 will be 90 drawn into contact with the carrier surface 95 145 at certain positions in the rotary path of the carrier and will be moved away from said surface in other positions, as will hereinafter appear. The outer face of the carrier 145 is provided with a relatively movable face portion which, in the present embodiment, comprises a head or plunger, 162, supported at the end of the radially movable plate 163 guided in the arm 144 of the lower carrier. Preferably the head 162 comprises 100 a relatively soft pad 164 in order not to deface the boxes when the labels contact therewith.
- The numeral 165 indicates a fixed plate 105 fastened to a bracket 166 on the table and the plate 165 is provided with a cam groove 167 surrounding the shaft 133, and a roller 168 on the plate 165 engages the groove 167 so that as the carrier rotates, movement of the head 162 is partially controlled. It will 110 be understood that each of the carriers of both series is of similar construction as above described for one of them. The plates 163 carrying the heads 162 are frictionally restrained in their radial movement, preferably by the provision, adjacent each of said plates, of a pin 162' having an enlarged head 163', said head being pressed against the adjacent plate 163 by a coil spring 164', as 115 illustrated in Fig. 25.
- In the present embodiment both the upper series of carriers and the lower series are moved in an endless path, and to this end mechanism is provided for intermittently 120 synchronously rotating the shafts 132 and 133.

133. The shaft 132 at one end has adjustably fixed thereto a large pinion 169 meshing with a small intermediate pinion 170, the latter in turn meshing with a large pinion 171 of the same size as the pinion 169 and connected to the shaft 133. Outside of the pinion 171 the shaft 133 is provided with a mutilated pinion 172 having four series of teeth 173 and intermediate larger teeth 174.
- 10 A mutilated gear 175 on the counter-shaft 63 has a series of teeth equal in number to each series 173 and a surface 176, which latter cooperates with the teeth 174. The periphery of the gear 175 adjacent the end of the series 15 of small teeth is so shaped that the initial engagement of the small teeth of said gear 175 with the series of small teeth 173 will serve to gradually start the rotation of the latter instead of at once causing a sudden 20 movement thereof. The operating mechanism described will cause the synchronous rotation of the several carriers in an intermittent manner and the carriers are so arranged as to come to rest at definite points 25 in their rotary path. One of the upper carriers will come to rest adjacent the glue transfer roller 53; the immediately preceding carrier will come to rest beneath the label magazine; the next preceding carrier 30 will come to rest adjacent a pressing device and the fourth carrier will come to rest directly opposite one of the lower series of carriers. The lower series of carriers will rotate in the same direction as the upper series 35 and the several carriers will come to rest, one in position to receive a box from the reciprocating box carrier, the next preceding adjacent certain label end folding devices and the next carrier adjacent a certain box 40 press into which the labeled boxes are ejected, all as will hereinafter appear.

Depending from the cross-piece 6 is a substantial bracket 179 supporting a disk 180 closely adjacent the radially movable arms 45 135 of the upper carrier. On the side of the disk 180 adjacent the arms, a circular way or groove 181 is provided and each of the arms 135 is provided with an anti-friction roller 182 engaging said groove. At diametrically disposed points in the disk 180, in line with the stationary points of the carriers when adjacent the label magazine and the uppermost carrier of the lower series, are radial grooves 183 in which slide blocks 184 50 provided with grooves adapted to aline with and form a part of the circular groove 181. The blocks 184 are simultaneously radially reciprocated by links 185 connected thereto and to arms 186 on an oscillatory sleeve 187 55 on the shaft 132, said sleeve being oscillated by a rod 188, one end of which is pivotally connected thereto at 189, the opposite end carrying a cam roller 190 engaging a cam groove 191 in a rotary disk 192 carried by 60 the countershaft 63.

Supported on brackets 193 attached to the frame castings is a press head 194 adapted to reciprocate to and from the carrier in position opposite thereto, and reciprocatory motion is communicated to said press head 70 by a connecting rod 195 pivoted to the oscillatory sleeve 187 at 196.

The cam groove 167 in the fixed disk 165 adjacent the lower carrier is of such form that as the carriers are rotated, the head 162 75 of any particular carrier will be flush with the surface 145 when in a position of rest opposite the adjacent carriers of the upper series, and the head will be maintained in this position and the succeeding position of 80 rest of the lower carrier until the box contacts therewith. When the box contacts therewith, however, it is designed to move both the label and the box inwardly of the carrier and said cam groove 167 is provided 85 with an enlarged portion 197 to permit such movement. The head retains an inner position through the next position of rest and until it reaches the position where the labeled box is to be ejected, whereupon it is 90 positively moved to eject the box. This last function is accomplished by means of a block 198 reciprocating in a radial groove 199 of the lower carrier and provided with a groove adapted to aline with the groove 167 and 95 form a part thereof. The anti-friction roller 168 is received by the groove in the block 198 whereupon outward radial movement is given the block through the instrumentality of a link 200 pivotally connected at 201 to 100 an oscillatory sleeve 202 on the shaft 133, said sleeve being oscillated by a rod 203 having a roller 204 operating in a cam groove 205 of a disk 206 on the counter-shaft 63. When the lowermost cam of the upper series 105 is at rest opposite the uppermost carrier of the lower series, it is designed to operate the head 139 to assist in stripping the label from the upper carrier and transferring it to the other, and the outward movement of the 110 head 139 is accomplished by a rock-lever 207 pivoted on the frame at 208 and having an end disposed opposite the position assumed by the spring-operated pin 140, said lever being operated at the proper time by a connecting rod 209 pivotally connected thereto 115 and to the oscillatory sleeve 202.

Label end folding devices.—Adjacent one of the positions of rest of the lower carriers, in the present embodiment, the lowest position, are located devices which complete the folding of the label on the box. In said position the lowermost carrier projects through an opening 210 in the table.

The numerals 211 and 212 indicate rock-levers fulcrumed at 213 on posts depending from the table top, one end of said rock-levers being pivoted to connecting rods 214 operated by rotary cams 215 on the transverse shaft 92. Each of said rock-levers is 120 130

connected by a link 216 to a finger-carrying frame or support 217 slideable in guideways 218 secured to the bottom of the table. Each of the frames 217 carries a folding device or finger, in the preferred form consisting of a roller 219 journaled in the outer ends of rock-arms 220 pivoted on the transverse rod 221 in the frame 217, each rock-arm 220 having a pin 222 engaged by one end of springs 223 coiled around the rod 221, the other ends of said springs engaging beneath an abutment 224 on the frame 217. The tension of the springs 223 is exerted to press the rollers 219 upwardly toward the plane 15 of the face of the adjacent carrier, and undue movement of said rollers in either direction is restricted by pins 225 on the frame 217 engaging slots 226 in the arms 220. The guiding grooves 227 in the ways 218 are 20 inclined in the direction of the face of the adjacent carrier so that the pressure of the rollers 219 against the box is at all times relatively strong. The operation of the respective rollers 219 is so timed that one 25 will advance and fold one end of the label down on the box and then retreat in time to permit the other end of the label to be folded upon the previously folded end.

Box press.—In rear, on a level with the 30 position assumed by the labeled boxes when in position to be ejected from the lower carrier, is a press into which the labeled boxes are successively pushed by the ejector of the carrier, each succeeding box advancing the one ahead of it. This press comprises upright side walls 228 and 229 spaced apart sufficiently to permit the boxes to pass therebetween, and one of said walls, as 228, is free to move toward and from the other 35 sufficiently to press the label on the box where disposed across the joint between the cover and the base of the box. Said movable side wall or press-head 228 is vibrated by a lever 230 fulcrumed on the frame at 231, one end of said lever having a slot 232 engaging a pin 233 on the wall 228 and the other end of said lever having a roller engagement with a cam groove in a cam disk 234 fast on a longitudinally rotary shaft 235 journaled in brackets beneath the table, said latter shaft being continuously driven from the shaft 92 by bevel gears 236, 237. In the present embodiment two presses are 40 employed through which the boxes successively pass, said presses and their operating devices being identical in construction, as 45 illustrated.

Slitter.—After passing through the presses 228, 229, the labeled boxes are operated upon 50 by a cutting device which slits the labels or covering strips on the boxes on a line opposite the joint on one side of the box, thus leaving the base and cover at the opposite side of the box hinged by the label. On the 55 shaft 235, at the extreme rear portion of the

machine, is a cam disk 238 which causes vertical oscillation of a rock-arm 239 pivoted at one end to a bracket 240 on the table and at its other end joined by a link 241 to a vertically guided reciprocating follower, or box-supporting head, 242, adapted to reciprocate in a guideway 243. Said guideway is transversely disposed relative to the path of the boxes in the pressing mechanism opposite the position of ejection of the labeled boxes from the lower rotary carrier and comprises front and rear walls 244, the former having an opening 245 to permit the labeled boxes to pass from said press into said guideway. The follower 242 has a depending vertically arranged extension in the shape of a plate 246 having oppositely disposed flanges 247 and said depending portion is slotted on opposite sides, as at 248, a series of anti-friction rollers 249 being journaled in the flanges 247 by the axles 250, to which said rollers are connected. The plate 246 reciprocates vertically in the transverse guideway and is held in alignment therewith by a suitable bracket 251 on the frame which bears on the front part thereof and by retaining plates 251, 251 fastened to the frame and bracket at the rear of the reciprocating plate and against which the anti-friction rollers 249 are adapted to 95 bear. By this construction the follower moves readily up and down under the influence of the rock-arm 239, and even though some adhesive should become attached to the follower or its guide, ready movement of the 100 former is permitted on account of the anti-friction rollers.

The boxes from the lower turret pass through the presses, which latter, in this instance, become in effect a supply magazine 105 for the slitter guideway, and as a labeled box is ejected from the lower turret the rearmost of the boxes in the press is thrust into the slitter guideway through the opening 245 and takes position upon the support 110 or follower 242, this latter being in its lower position at that time. A resilient plate 252 rests upon the tops of the boxes in the magazine and guides them through the opening 245, the forward end of said plate 252 being 115 curved upwardly and terminating at a point preferably spaced from the path of the boxes when moved in the guideway transversely of said press. On the guideway wall 244 opposite the opening 245 is removably and adjustably secured a label-smoothing and pressing device comprising brushes 253 removably attached to a plate 254, said brushes being adapted to contact with the labels on the boxes and smooth and press the same 120 thereagainst as the boxes are lifted by the follower 242. The brushes being spaced apart, the overlapping edge of the label will not be disturbed thereby. Above the opening 245, in the forward plate 244, is a horizontal 125

rotary shaft 255 having removably secured thereto a label-slitting or severing means which, in the present instance, comprises a metallic disk 256 having a sharp cutting edge, which latter is disposed to project slightly into the guideway through a slot 257 which may be formed in the latter, said disk being disposed in line with the joint at one side of the box as said box is fed by the follower 242. Thus, as the follower is lifted the box is fed past said slitter and the label is severed at one side thereof in line with the joint between the box sections, the other side remaining whole and serving as a hinge for said sections. Directly opposite said slitter is a pressing roller 258 journaled on the guideway, and projecting into said guideway in line with the joint of the boxes opposite the severed portion of the label, said roller 258 being adapted to firmly press the label at the joint in order to secure its more efficient attachment at this point and also to press the box toward the slitting disk 256. As particles of glue from the boxes might adhere to the walls of the guideway and obstruct free movement of the boxes therethrough, said walls are provided with oppositely disposed anti-friction rollers 259, so that free movement of the boxes will be permitted, and at the same time said boxes will be guided in proper position relatively to said slitter and the roller 258. The slitter shaft 255 is supported in bearing boxes fastened to each of two upright yokes 260 and 261, and is provided with a small bevel gear 262 meshing with a larger bevel gear 268 on a shaft 264 continuously driven from the main driving shaft 10 through the instrumentality of a sprocket and chain 265, as illustrated. The slitter revolves very rapidly and makes a very fine cut in the labels, so that the resultant ends thereof are substantially even.

The follower 242 not only feeds the boxes past the slitter, but beyond the same into position in rear of a pusher or ejector 266, which latter in turn moves rearwardly and pushes the box off the follower and preferably onto a platform 267 having lateral walls 268, spring-held box-retaining dogs 269 having beveled faces 270 serving to prevent the boxes from returning into the path of movement of a succeeding box through the guideway. Each dog 269 comprises a plate 271 pivoted at 272 to a wall 268, said walls each having an opening 273 through which the beveled faces of the dogs project. A spring 274 serves to maintain the boxes in upright position immediately adjacent the guideway.

The pusher 266 reciprocates horizontally opposite the uppermost position of the boxes and passes between the lateral walls of the guideway. Said pusher comprises a plate 65 which is the termination of a rectangular

reciprocating rod 275, mounted to slide in bearings on the upper portion of the yokes 260 and 261. On the countershaft 63 is a face cam 276 engaged by a roller of a cam rod 277, the adjacent end of which latter is slotted and embraces the shaft 63. The remote end of the rod 277 is bent upwardly and slides in a bracket 278 adjustably fastened at the upper lateral portion of the yoke 261. To the end of the rod 277 is adjustably fixed a laterally disposed connecting piece 279, which latter is also adjustably fastened to the pusher rod 275. Thus, as the shaft 63 rotates, reciprocating motion is imparted to the pusher rod 275 through the connecting 75 instrumentalities just described, so that after each box is slit, it is removed from the slitter guideway by said pusher. The guide walls 244, 244 are preferably cast as a part of substantial frame pieces 280, 280, bolted 80 in position at the rear end of the table 1, which frame pieces serve as supports for the platform 267 and other adjacent parts hereinbefore described.

The operation of the machine will be largely apparent from the above description, but in order that many of the important advantages secured by the machine may be clearly brought out, a detailed description of the operation follows: A pack 95 of labels or other flexible paper strips with which the boxes are to be covered is placed in the label magazine between the label-holding fingers 40 with the bottom label of the pack resting upon the flanges 41. 100 The position of the lower part of the fingers 40 is adjusted by the screws 39 so that the pack will be efficiently supported with the bottom label in condition to be withdrawn downwardly. If the labels are provided on one face with ornamentation or printing, etc., it is to be understood that the pack is so arranged that the ornamental or printed face of each label will be uppermost. The attendant fills the box magazine with 110 boxes, placing them upon the belt 79 and the machine is then started by moving the shifting lever 19 to cause the engagement of the clutch elements 12 and 13, it being assumed that the belt pulley 11 is being continuously driven from some suitable source of power.

It will simplify the description if the progress of one of the labels and the box to be assembled therewith be followed 115 through the various operations of the machine. As the upper carrier shaft 132 rotates, one of its carriers will come to rest adjacent the glue transfer roller 53, and while thus at rest said transfer roller, which 120 has received a coating of glue from the tank, will move up and down in contact with the pad 137, which latter will receive a coat of glue, after which the glue transfer roller will assume position in contact 125 130

with the delivery roller 47 for the reception of glue for the succeeding carrier. The first carrier then moves upwardly and comes to rest immediately beneath but close to the bottom label in the magazine, and when in this position the anti-friction roller 182 will occupy the transverse groove in the block 184. In this position of the parts, said block will be moved radially outward by the operating mechanism previously described and the glued face of said carrier will be pressed against the bottom label of the pack of labels. When the block 184 retreats, said bottom label, adhering to the carrier, will be withdrawn from the pack, and the withdrawn label will thus become covered with the glue on one face, the disposition of the glue on the label being governed by the requirements for use, it sufficing, in the present embodiment, that glue shall be distributed on the label to effect a smooth union with the box and especially that the glue shall be applied to the opposite ends thereof. The carrier referred to next moves down and comes to rest opposite the label press 194, whereupon the press-head advances and presses the label against the carrier and at the same time smooths the label thereon. Said carrier then moves to its lowermost position and when at rest will be directly opposite one of the lower carriers, which latter will be in its uppermost position. The combined gripping and stripping fingers or jaws 148 will have passed into the recess 143 in the upper carrier, thus assuming position beneath the label carried thereby. While the upper and lower carriers are in this position of rest in their rotary paths, the lower block 184 will be moved radially outward and the label on the upper carrier will be transferred to the face of the lower carrier, the inward radial movement of the jaws 148 assisting in this transfer, gripping an intermediate part of the coated label to the lower carrier while the label is adhering to the upper carrier and finally serving to retain the label on the lower carrier by pressing thereagainst. Not only do the fingers 148 retain the label on the lower carrier, but the label is stretched by the engagement of the fingers 149 with the grooves in the lower carrier, the label being thus smoothed and tautened at the place where the box is to be first applied thereto. On the upper carrier the adhesive coated face of the label will be in contact with the pad 137, and by transferring the label to the lower carrier, as just explained, the adhesive face of the label will be presented outward, the material of the label being interposed between its adhesive face and the lower or second carrier. It will thus be in position to readily receive a box or other article on its adhesive face. The lower carrier rotates in the same direction as the upper carrier, and when the lower carrier has received the label it moves downwardly, and the label carried thereby will assume position directly opposite the path of movement of the box carrier, with the jaws 148 gripping the label to the carrier. Thereupon a box, which will have been moved from the box magazine into the reciprocating box carrier, will in turn be moved and pressed against the outwardly facing glued surface of said label, and at this time the head 162 will be in its outermost position so that a relatively strong pressure of the label against the box is secured. The reciprocating carrier jaws are so designed that the box projects somewhat beyond the same. As soon as the box is pressed against the label, the jaws 148 release the label, the cam 157 being moved to accomplish the releasing movement of the jaws 148. The box carrier presses the box into the recess 146, the enlarged portion 197 of the cam groove 167 permitting the head 162 to be rapidly moved inwardly with the box. As the box moves inwardly the intermediate portions of the label are folded and smoothed against the sides of the box across the joint between the cover and the base by the brushes 147. The detaining rod 121 remains at rest during the first part of the retreating movement of the box carrier, thus serving to positively eject the box from the carrier jaws. When the label is released by the jaws 148, the ends thereof may have a tendency to curl, and in order to avoid curling as much as possible, arms 300 are placed one on each side of the machine frame adjacent the label in this position of rest, so that, should the label curl when released from the grip of the arms 148, each end face will come into contact with said arms before curling to any great extent, and further curling will be prevented.

The intermediate portion of the label having been folded and smoothed on the sides of the box, the lower carrier moves to its lowermost position with the box label in partly folded condition thereon. After the carrier comes to rest in its lowermost position, the rollers 219 move against the respective depending end portions of the label, and their motion being continued on to the surface of the box, such end portions are folded upon the adjacent face of the box. Preferably the boxes assemble with the label to one side of the central portion of the latter, so that the depending ends of the label referred to are of unequal length, and the roller 219, which cooperates with the longer depending end, moves in advance of the other similar roller and a portion of the ends of the label thus becomes superposed, and at the same time adhesively attached to each other and to the surface of 180

the box. The inclined guideways 227 cause the pressure of the rollers 219 against the label to be slightly increased during the folding operation, and in a measure the ends 5 of the label are wiped on the box in such a manner that they are slightly stretched, the completed article presenting a smooth label surface except for the joint. The lower carrier then makes a further revolution 10 and the wrapped box is carried upward to the next position of rest, where it will be adjacent the box press; and when it has assumed this position, the roller 168 attached to the head 162 will occupy the transverse slot of the radially movable block 198, whereupon outward radial movement of the block 198 is caused by the cam 205 and the head 162 thereby moved radially outward, thus ejecting the wrapped box from 15 the lower carrier and thrusting or pushing it into the press. The boxes enter the press one after the other, as will be clear, each succeeding box following those ahead of it, and as they pass through the press, the vibration of the movable press wall further presses the label on the box on the jointed faces, thereby causing the label to securely 20 adhere at such parts.

It will be observed that both the upper 25 and lower carriers comprise four carrier plates diametrically disposed in pairs at angles of 90 degrees and that the operations just explained relative to a single carrier plate apply to each. By providing a plurality of said carrier plates, the capacity of the machine is increased and its construction simplified. The diametrically disposed pads 137, when in vertical position, are respectively disposed one opposite the label magazine and the other opposite the lower carrier, and advantage is taken of this fact and the radial movements of the upper carriers accomplished by a single operating mechanism, as will be clear from the foregoing. From the box press the wrapped and pressed boxes successively pass through the slitting device hereinbefore described, and are finally ejected from the machine as completely labeled two-part or sectional 40 boxes, ready for the reception of goods, such as cigarettes, etc.

From the foregoing it will be perceived that a machine is produced capable of accomplishing, among others, the objects hereinbefore referred to in a practical and efficient manner.

As many changes could be made in the above construction and many apparently widely different embodiments of this invention could be made without departing from the scope thereof, it is intended that all matter contained in the above description or shown in the accompanying drawings shall be interpreted as illustrative and not in a 55 limiting sense. It is also to be understood

that the language used in the following claims is intended to cover all of the generic and specific features of the invention herein described and all statements of the scope of the invention, which, as a matter of language, might be said to fall therebetween. 70

Having described my invention, what I claim as new and desire to secure by Letters Patent is:

1. In an apparatus of the character described, in combination, a carrier, a label supply device, means adapted to cause a label of the supply to be adhesively attached to said carrier, a second label carrier comprising label folding devices, means adapted to transfer said label from the first-mentioned carrier to the second carrier and interpose the material of the label between the adhesive face thereof and said second carrier, and means adapted to move an article 75 against the label on the second carrier and with said label relatively to the label folding devices, thereby causing the label to be folded against the opposite sides of the article and adhesively attached thereto. 80

2. In an apparatus of the character described, in combination, a carrier, a label supply device, means adapted to cause a label of the supply to be adhesively attached to said carrier, a second label carrier comprising label folding devices, means adapted to transfer said label from the first-mentioned carrier to the second carrier and interpose the material of the label between the adhesive face thereof and said second carrier, means adapted to move an article 95 against the intermediate portion of said label on the second carrier and with said label relatively to the label-folding devices, thereby causing the label to be folded 100 against the opposite sides of the article and adhesively attached thereto, and means adapted to fold the ends of said label against said article. 105

3. In an apparatus of the character described, in combination, a carrier, a label supply device, means adapted to cause a label of the supply to be adhesively attached to said carrier, a second label carrier comprising label folding devices, means adapted to transfer said label from the first-mentioned carrier to the second carrier and interpose the material of the label between the adhesive face thereof and said second carrier, means adapted to move an article 110 against the intermediate portion of said label on the second carrier and with said label relatively to the label-folding devices, thereby causing the label to be folded 115 against the opposite sides of the article and adhesively attached thereto, and means adapted to fold the ends of said label on the article and adhesively attach them one over the other. 120

4. In an apparatus of the character de- 125

scribed, in combination, a carrier movable in an endless path, a label supply device, means adapted to move said carrier at an angle to its endless path and cause a label of the supply to be adhesively attached thereto, a second label carrier movable in an endless path, means adapted to transfer said label from the first-mentioned carrier to the second carrier and interpose the material of the label between the adhesive face thereof and said second carrier, and means adapted to assemble the label on the second carrier with an article.

5. In an apparatus of the character described, in combination, a carrier movable in an endless path, a label supply device, means adapted to cause a label of the supply to be adhesively attached to said carrier, a second carrier movable in an endless path 10 and comprising label-folding devices, means adapted to transfer said label from the first-mentioned carrier to the second carrier and interpose the material of the label between the adhesive face thereof and said second carrier, and means adapted to move an article against the label on the second carrier and with said label relative to the label-folding devices, thereby causing the label to be folded against the opposite sides of the 25 article and adhesively attached thereto.

6. In an apparatus of the character described, in combination, a carrier movable in an endless path, a label supply device, means adapted to move said carrier at an angle to its endless path and cause a label of the supply to be adhesively attached thereto, a second label carrier movable in an endless path, means adapted to move said first-mentioned carrier toward said second carrier and transfer said label thereto so as to 30 interpose the material of the label between the adhesive face of the label and said second carrier, and means adapted to assemble the label on the second carrier with an article.

7. In an apparatus of the character described, in combination, a carrier movable in an endless path, a label supply device, means adapted to apply adhesive to said carrier, means adapted to move said carrier at an angle to its endless path and cause a label of the supply to be pressed against the adhesive face of the carrier, a second label carrier movable in an endless path, means adapted to move said first-mentioned carrier toward said second carrier and transfer said label thereto so as to interpose the material of the label between the adhesive face of the label and said second carrier, and means adapted to assemble the label on the second carrier with an article.

8. In an apparatus of the character described, in combination, a carrier movable in an endless path, a label supply device, means adapted to apply adhesive to said

carrier, means adapted to move said carrier at an angle to its endless path and cause a label of the supply to be pressed against the adhesive face of the carrier, a second label carrier movable in an endless path and comprising label-folding devices, means adapted to move said first-mentioned carrier toward said second carrier and transfer said label thereto so as to interpose the material of the label between the adhesive face of the label and said second carrier, and means adapted to move an article against the label on the second carrier and with said label relatively to said label-folding devices, thereby causing the label to be folded against the opposite sides of the article.

9. In an apparatus of the character described, in combination, a carrier movable in an endless path, a label supply device, means adapted to cause a label of the supply to be adhesively attached to said carrier, separate means adapted to press the adhering label against the carrier, a second carrier movable in an endless path, means adapted to transfer said label from the first-mentioned carrier to the second carrier and interpose the material of the label between the adhesive face thereof and said second carrier, and means adapted to assemble the label on the second carrier with an article.

10. In an apparatus of the character described, in combination, a carrier movable in an endless path, a label supply device, an adhesive supply, movable means adapted to transfer adhesive from said supply to said carrier, means adapted to cause a label of the supply to be pressed against and thereby adhere to the adhesive face of said carrier, means adapted to separately press the adhering label against said carrier, a second label carrier movable in an endless path, means adapted to transfer said label from the first-mentioned carrier to the second carrier and interpose the material of the label between the adhesive face thereof and said second carrier, and means adapted to assemble the label on the second carrier with an article.

11. In an apparatus of the character described, in combination, a carrier movable in an endless path, a label supply device, an adhesive supply, means adapted to move from the adhesive supply against said carrier to apply adhesive to the carrier, means adapted to move said carrier at an angle to its endless path and cause a label of the supply to be pressed against the adhesive face of the carrier, a second label carrier movable in an endless path, means adapted to move said first-mentioned carrier toward said second carrier and transfer said label thereto so as to interpose the material of the label between the adhesive face of the label and said second carrier, and means

adapted to assemble the label on the second carrier with an article.

12. In an apparatus of the character described, in combination, a carrier movable in an endless path, a label supply device, an adhesive supply, movable means adapted to transfer adhesive from said supply to said carrier, means adapted to move said carrier at an angle to its endless path and cause a label of the supply to be pressed against and thereby adhere to the adhesive face of said carrier, means adapted to separately press the adhering label against said carrier, a second label carrier movable in an endless path, means adapted to move said first-mentioned carrier toward said second carrier and transfer said label thereto so as to interpose the material of the label between the adhesive face of the label and said second carrier, and means adapted to assemble the label on the second carrier with an article.

13. In an apparatus of the character described, in combination, a carrier intermittently movable in an endless path, a label supply device, means adapted to move said carrier at an angle to its endless path at a point of rest in said path and cause a label of the supply to be adhesively attached thereto, a second label carrier intermittently movable in an endless path, means adapted to transfer said label from the first-mentioned carrier to the second carrier at a point of rest in said endless path and interpose the material of the label between the adhesive face of said label and the second carrier, and means adapted to assemble the label on the second carrier with an article.

14. In an apparatus of the character described, in combination, a carrier intermittently movable in an endless path, a label supply device, means adapted to move said carrier at an angle to its endless path at a point of rest in said path and cause a label of the supply to be adhesively attached thereto, a second label carrier intermittently movable in an endless path, means adapted to move said first-mentioned carrier toward said second carrier at a point of rest in its endless path and transfer said label to the second carrier so as to interpose the material of said label between the adhesive face of said label and said second carrier, and means adapted to assemble the label on the second carrier with an article.

15. In an apparatus of the character described, in combination, a carrier intermittently movable in an endless path, a label supply device, means adapted to move said carrier at an angle to its endless path at a point of rest in said path and cause a label of the supply to be adhesively attached thereto, a second label carrier intermittently movable in an endless path, and means adapted to

move an article against the label on the second carrier and attach the label to the article when said second carrier is at rest.

16. In an apparatus of the character described, in combination, a carrier intermittently movable in an endless path, a label supply device, means adapted to move said carrier at an angle to its endless path at a point of rest in said path and cause a label of the supply to be adhesively attached thereto, a second label carrier intermittently movable in an endless path, and means adapted to move an article against the label on the second carrier and fold the same on the article when the second carrier is at rest.

17. In an apparatus of the character described, in combination, a carrier intermittently movable in an endless path, a label supply device, means adapted to move said carrier at an angle to its endless path at a point of rest in said path and cause a label of the supply to be adhesively attached thereto, a second label carrier intermittently movable in an endless path, and mechanism adapted to fold the label on the second carrier on an article, comprising means adapted to move an article against the label on the second carrier and partially fold the label on said article while the second carrier is at rest, and means adapted to further fold the label on said article at a different point of rest of the second carrier.

18. In an apparatus of the character described, in combination, a carrier intermittently movable in an endless path, a label supply device, means adapted to apply adhesive to said carrier, means adapted to move said carrier at an angle to its endless path at a point of rest in said path and cause a label of the supply to be pressed against and adhere to the adhesive face of said carrier, a second label carrier intermittently movable in an endless path, means adapted to move said first-mentioned carrier at an angle to its endless path at a different point of rest in its path and cause the transfer of said adhering label to said second carrier with the material of the label between the adhesive face of said label and the second carrier, and means adapted to move an article against the label and fold the label on the article at a point of rest in the endless path of said second carrier.

19. In an apparatus of the character described, in combination, a carrier intermittently movable in an endless path, a label supply device, an adhesive supply, movable means adapted to apply adhesive to said carrier, means adapted to move said carrier at an angle to its endless path at a point of rest in said path and cause a label of the supply to be pressed against and adhere to the adhesive face of said carrier, a second

label carrier intermittently movable in an endless path, means adapted to move said first-mentioned carrier at an angle to its endless path at a different point of rest in its path and cause the transfer of said adhering label to said second carrier with the material of the label between the adhesive face of said label and the second carrier, and means adapted to move an article against 10 the label and fold the label on the article at a point of rest in the endless path of said second carrier.

20. In an apparatus of the character described, in combination, a carrier intermittently movable in an endless path, a label supply device, means adapted to apply adhesive to said carrier, means adapted to move said carrier at an angle to its endless path at a point of rest in said path and cause a label of the supply to be pressed against and adhere to the adhesive face of said carrier, movable means adapted to press the adhering label against said carrier at another point of rest in its endless path, a 25 second label carrier intermittently movable in an endless path, means adapted to move said first-mentioned carrier at an angle to its endless path at a different point of rest in its path and cause the transfer of said 30 adhering label to said second carrier with the material of the label between the adhesive face of said label and the second carrier, and means adapted to move an article against the label and fold the label on the 35 article at a point of rest in the endless path of said second carrier.

21. In an apparatus of the character described, in combination, a carrier, a label supply device, means adapted to cause a label of the supply to be adhesively attached to said carrier, a second label carrier comprising label-folding devices, means adapted to transfer said label from the first-mentioned carrier to the second carrier and 40 interpose the material of the label between the adhesive face thereof and said second carrier, means adapted to move an article against the label on the second carrier and with said label relatively to the label-folding 45 devices, thereby causing the label to be folded against the opposite sides of the article and adhesively attached thereto, and means adapted to eject the labeled article from the carrier.

55. 22. In an apparatus of the character described, in combination, a carrier movable in an endless path, a label supply device, means adapted to cause a label of the supply to be adhesively attached to said carrier, a second carrier movable in an endless path and comprising label-folding devices, means adapted to transfer said label from the first-mentioned carrier to the second carrier and interpose the material of the

label between the adhesive face thereof and 65 said second carrier, means adapted to move an article against the label on the second carrier and with said label relative to the label-folding devices, thereby causing the label to be folded against the opposite sides 70 of the article and adhesively attached thereto, and means movable with said second carrier adapted to eject the labeled article therefrom.

23. In an apparatus of the character described, in combination, a carrier intermittently movable in an endless path, a label supply device, means adapted to move said carrier at an angle to its endless path at a point of rest in said path and cause a label 80 of the supply to be adhesively attached thereto, a second label carrier intermittently movable in an endless path comprising label-folding devices, means adapted to move said first-mentioned carrier toward 85 said second carrier to a point of rest in its endless path and transfer said label to the second carrier so as to interpose the material of said label between the adhesive face of said label and said second carrier, mechanism adapted to fold the label on the second carrier on an article comprising means adapted to move an article against the label on the second carrier and partially fold the label on said article while the second carrier 90 is at rest, means adapted to further fold the label on said article at a different point of rest of the second carrier, and means movable with said second carrier adapted 95 to eject the labeled article therefrom at a 100 point of rest in the endless path of the second carrier.

24. In an apparatus of the character described, in combination, an intermittently movable rotatable carrier, a label supply device, means adapted to move said carrier radially at a point of rest in its rotary path and cause a label of the supply to be adhesively attached thereto, a second intermittently movable rotatable carrier, means 105 adapted to move said first-mentioned carrier radially at a different point of rest in its rotary path and transfer said label therefrom to the second carrier and interpose the material of the label between the adhesive 110 face of the label and the second carrier, and means adapted to assemble the label on the second carrier with an article.

25. In an apparatus of the character described, in combination, an intermittently 120 movable rotatable carrier, a label supply device, means adapted to move said carrier radially at a point of rest in its rotary path and cause a label of the supply to be adhesively attached thereto, a second intermittently movable rotatable carrier, means adapted to move said first-mentioned carrier radially at a different point of rest in 125

- its rotary path and transfer said label therefrom to the second carrier and interpose the material of the label between the adhesive face of the label and the second carrier, and
- 5 means adapted to assemble the label on the second carrier with an article at a second different point of rest in its rotary path.
26. In an apparatus of the character described, in combination, a carrier having a
- 10 recess in its label supporting face, a label supply device, means adapted to cause a label of the supply to be adhesively attached to said carrier, a second carrier, means comprising a stripper on the second carrier disposed to move in said recess and adapted to transfer said label from the first-mentioned carrier to the second carrier and interpose the material of the label between the adhesive face thereof and said second carrier,
- 15 and means adapted to assemble the label on the second carrier with an article.
27. In an apparatus of the character described, in combination, a carrier having a recess in its label supporting face, a label
- 20 supply device, means adapted to cause a label of the supply to be adhesively attached to said carrier, a second carrier, means comprising strippers on the second carrier disposed to operate in said recesses and adapted to transfer said label from the first-mentioned carrier to the second carrier and interpose the material of the label between the adhesive face thereof and said second carrier, means adapted to cause said strippers
- 25 to hold said label on the second carrier, and means adapted to assemble the label on the second carrier with an article.
28. In an apparatus of the character described, in combination, a carrier having recesses in its label supporting face and movable in an endless path, a label supply device, means adapted to cause a label of the supply to be adhesively attached to said carrier, a second carrier movable in an endless
- 30 path, means comprising strippers on the second carrier adapted to move in said recesses and to transfer said label from the first-mentioned carrier and press the same against the second carrier with the material
- 35 of the label between the adhesive face thereof and said second carrier, and means adapted to assemble the label on the second carrier with an article.
29. In an apparatus of the character described, in combination, a carrier having recesses in its label supporting face and movable in an endless path, a label supply device, means adapted to cause a label of the supply to be adhesively attached to said carrier, a
- 40 second carrier movable in an endless path, means comprising reciprocatory strippers on the second carrier adapted to move in said recesses and to transfer said label from the first-mentioned carrier and press the same
- 45 against the second carrier with the material
- of the label between the adhesive face thereof and said second carrier, and means adapted to assemble the label on the second carrier with an article.
30. In an apparatus of the character described, in combination, an intermittently rotatable support, a series of carriers movably connected thereto, a label magazine, means adapted to apply glue to said carriers, means adapted to reciprocate said carriers relatively to said support in line with the labels of the magazine when the support is at rest, whereby labels become adhesively attached to said respective carriers, a second intermittently rotatable series of carriers,
- 50 means adapted to successively transfer the labels on the first series of carriers to the second series, respectively, and dispose said labels on the second series with the glued side out, and means adapted to successively assemble articles with the labels carried by the second series of carriers.
31. In an apparatus of the character described, in combination, an intermittently rotatable support, a series of carriers movably connected to said support in oppositely disposed pairs, a label magazine opposite a position of rest in the rotary path of said carriers, means adapted to apply glue to said carriers, a fixed member having guides at oppositely disposed positions of rest in said rotary path in line with said magazine, carrier-engaging devices slidable on said guides, a second series of carriers rotatable synchronously with the first series, means adapted to simultaneously reciprocate said carrier-engaging devices when engaged by carriers of the first series, and thereby successively transfer labels from said magazine to the first series of carriers, respectively,
- 55 and from the first series to the second, and dispose said labels on the second series with the glued side out, and means adapted to successively assemble articles with the labels carried by the second series of carriers.
32. In an apparatus of the character described, in combination, an intermittently rotatable support, a series of carriers movably connected to said support in oppositely disposed pairs, a label magazine opposite a position of rest in the rotary path of said carriers, means adapted to apply glue to said carriers, a fixed member having curved guides and oppositely disposed radial guides located at positions of rest in said rotary path in line with said magazine, carrier-engaging devices slidable on said radial guides and having guides adapted to align with said curved guides, a second series of carriers rotatable synchronously with the first series, means adapted to simultaneously reciprocate said carrier-engaging devices when engaged by carriers of the first series and thereby successively transfer labels from said magazine to the first series of carriers, respec-

- tively, and from the first series to the second, and dispose said labels on the second series with the glued side out, and means adapted to successively assemble boxes with the labels carried by the second series of carriers.
33. In an apparatus of the character described, in combination, an intermittently rotatable support, a series of carriers movably connected to said support in oppositely disposed pairs, a label magazine opposite a position of rest in the rotary path of said carriers, means adapted to apply glue to said carriers, a fixed member having guides at oppositely disposed positions of rest in said rotary path in line with said magazine, carrier-engaging devices slidable on said guides, a second series of carriers rotatable synchronously with the first series, means adapted to simultaneously reciprocate said carrier-engaging devices when engaged by carriers of the first series, and thereby successively transfer labels from said magazine to the first series of carriers, respectively, and from the first series to the second, and dispose said labels on the second series with the glued side out, comprising a rocker element concentric with said support, links connecting said rocker element with said carrier-engaging devices, and means adapted to successively assemble boxes with the labels carried by the second series of carriers.
34. In an apparatus of the character described, in combination, an intermittently rotatable support, a series of carriers movably connected to said support in oppositely disposed pairs, a label magazine opposite a position of rest in the rotary path of said carriers, means adapted to apply glue to said carriers, a label presser opposite another position of rest in said rotary path, a fixed member having curved guides and oppositely disposed radial guides located at positions of rest in said rotary path in line with said magazine, carrier-engaging devices slidable on said radial guides and having guides adapted to align with said curved guides, a second series of carriers rotatable synchronously with the first series, means adapted to simultaneously reciprocate said carrier-engaging devices when engaged by carriers of the first series, and thereby successively transfer labels from said magazine to the first series of carriers, respectively, and from the first series to the second, and dispose said labels on the second series with the glued side out, comprising a rocker element concentric with said support, links connecting said rocker element with said carrier-engaging devices and with said label presser, and means adapted to successively assemble boxes with the labels carried by the second series of carriers.
35. In an apparatus of the character described, in combination, an intermittently
- rotatable support, a series of carriers movably connected thereto, a label magazine, means adapted to apply glue to said carriers, means adapted to reciprocate said carriers relatively to said support in line with the labels of the magazine when the support is at rest, whereby labels become adhesively attached to said respective carriers, a presser, means to move the presser to and from the labels on said respective carriers when said carriers are at rest, a second intermittently rotatable series of carriers, means adapted to successively transfer the labels on the first series of carriers to the second series, respectively, and dispose said labels on the second series with the glued side out, and means adapted to successively assemble boxes with the labels carried by the second series of carriers.
36. In an apparatus of the character described, in combination, an intermittently rotatable support, a series of carriers movably connected thereto, a label magazine, a glue roller, means to move said roller on the face of the carriers to apply glue thereto, means adapted to reciprocate said carriers relatively to said support in line with the labels of the magazine when the support is at rest, whereby labels become adhesively attached to said respective carriers, a second intermittently rotatable series of carriers, means adapted to successively transfer the labels on the first series of carriers to the second series, respectively, and dispose said labels on the second series with the glued side out, and means adapted to successively assemble boxes with the labels carried by the second series of carriers.
37. In an apparatus of the character described, in combination, an intermittently rotatable support, a series of carriers movably connected thereto, a label magazine, a glue roller, means to move said roller on the face of the carriers when said carriers are at rest to apply glue thereto, means adapted to reciprocate said carriers relatively to said support in line with the labels of the magazine when the support is at rest, whereby labels become adhesively attached to said respective carriers, a second intermittently rotatable series of carriers, means adapted to successively transfer the labels on the first series of carriers to the second series, respectively, and dispose said labels on the second series with the glued side out, and means adapted to successively assemble boxes with the labels carried by the second series of carriers.
38. In an apparatus of the character described, in combination, an intermittently rotatable support, a series of carriers movably connected thereto, a label magazine, means adapted to apply glue to said carriers, means adapted to reciprocate said carriers relatively to said support in line with

the labels of the magazine when the support is at rest, whereby labels become adhesively attached to said respective carriers, a second intermittently rotatable series of carriers rotatable synchronously with the first series, reciprocatory jaws for each carrier of said second series rotatable therewith, means adapted to successively reciprocate the carriers of the first series relatively to those of the second and thereby apply the labels carried by the first series on the second, means to cause said jaws to press the labels against the carriers of the second series, and means adapted to successively assemble articles with the labels carried by the second series.

39. In an apparatus of the character described, in combination, an intermittently rotatable support, a series of carriers movably connected thereto, a label magazine, means adapted to apply glue to said carriers, means adapted to reciprocate said carriers relatively to said support in line with the labels of the magazine when the support is at rest, whereby labels become adhesively attached to said respective carriers, a second intermittently rotatable series of carriers rotatable synchronously with the first series, reciprocatory jaws for each carrier of said second series rotatable therewith, means adapted to successively reciprocate the carriers of the first series relatively to those of the second and thereby move the labels carried by the first series toward the second, means to cause said jaws to transfer the labels from the carriers of the first series to those of the second, and means adapted to successively assemble articles with the labels carried by the second series.

40. In an apparatus of the character described, in combination, an intermittently rotatable support, a series of carriers movably connected thereto, a label magazine, means adapted to apply glue to said carriers, means adapted to reciprocate said carriers relatively to said support in line with the labels of the magazine when the support is at rest, whereby labels become adhesively attached to said respective carriers, a second intermittently rotatable series of carriers rotatable synchronously with the first series, reciprocatory jaws for each carrier of said second series rotatable therewith, means adapted to successively reciprocate the carriers of the first series relatively to those of the second and thereby move the labels carried by the first series toward the second, means to cause said jaws to transfer the labels from the carriers of the first series to those of the second and hold the same thereon, and means adapted to successively assemble boxes with the labels carried by the second series.

41. In an apparatus of the character de-

scribed, in combination, an intermittently rotatable support, a series of carriers movably connected thereto, a label magazine, means adapted to apply glue to said carriers, means adapted to reciprocate said carriers relatively to said support in line with the labels of the magazine when the support is at rest whereby labels become adhesively attached to said respective carriers, a second intermittently rotatable series of carriers rotatable synchronously with the first series, reciprocatory jaws for each carrier of said second series rotatable therewith, means adapted to successively reciprocate the carriers of the first series relatively to those of the second and thereby apply the labels carried by the first series on the second, means to cause said jaws to press the labels against the carriers of the second series, means whereby the movement of said jaws to pressing position causes the label to be stretched, and means adapted to successively assemble boxes with the labels carried by the second series.

42. In an apparatus of the character described, in combination, an intermittently rotatable support, a series of carriers movably connected thereto, a label magazine, means adapted to apply glue to said carriers, means adapted to reciprocate said carriers relatively to said support in line with the labels of the magazine when the support is at rest, whereby labels become adhesively attached to said respective carriers, a second intermittently rotatable series of carriers rotatable synchronously with the first series, reciprocatory jaws slidably mounted on said second carriers, rock arms on said second carriers co-operatively connected to said jaws, means adapted to successively reciprocate the carriers of the first series relatively to those of the second and thereby apply the labels carried thereby on the second series, means adapted to successively rock said arms and cause said jaws to press said labels against the second carrier to which it has been applied, and means adapted to successively assemble boxes with the labels carried by the second series.

43. In an apparatus of the character described, in combination, an intermittently rotatable support, a series of carriers movably connected thereto, a label magazine, means adapted to apply glue to said carriers, means adapted to reciprocate said carriers relatively to said support in line with the labels of the magazine when the support is at rest, whereby labels become adhesively attached to said respective carriers, a second intermittently rotatable series of carriers rotatable synchronously with the first series, reciprocatory jaws slidably mounted on said second carriers and disposed opposite the peripheral face

- thereof, recesses in said face adapted to be engaged by said jaws, rock arms on said second carriers coöperatively connected to said jaws, means adapted to successively reciprocate the carriers of the first series relatively to those of the second and thereby apply the labels carried thereby on the second series, means adapted to successively rock said arms and cause said jaws to engage said recesses and press and stretch said labels against the second carrier to which it has been applied, and means adapted to successively assemble boxes with the labels carried by the second series.
44. In an apparatus of the character described, in combination, an intermittently rotatable support, a series of carriers movably connected thereto, a label magazine, means adapted to apply glue to said carriers, means adapted to reciprocate said carriers relatively to said support in line with the labels of the magazine when the support is at rest, whereby labels become adhesively attached to said respective carriers, a second intermittently rotatable series of carriers rotatable synchronously with the first series, reciprocatory jaws slidably mounted on said second carriers, rock arms on said second carriers coöperatively connected to said jaws, means adapted to successively reciprocate the carriers of the first series relatively to those of the second and thereby apply the labels carried thereby on the second series, means comprising an oscillatory cam with which said arms engage adapted to successively rock said arms and cause said jaws to press said labels against the second carrier to which it has been applied, and means adapted to successively assemble boxes with the labels carried by the second series.
45. In an apparatus of the character described, in combination, an intermittently rotatable support, a series of carriers movably connected thereto, a label magazine, means adapted to apply glue to said carriers, means adapted to reciprocate said carriers relatively to said support in line with the labels of the magazine when the support is at rest, whereby labels become adhesively attached to said respective carriers, a second intermittently rotatable series of carriers rotatable synchronously with the first series, reciprocatory jaws slidably mounted on said second carriers, rock arms on said second carriers coöperatively connected to said jaws, means adapted to successively reciprocate the carriers of the first series relatively to those of the second and thereby apply the labels carried thereby on the second series, an oscillatory cam with which said arms engage adapted to positively successively rock said arms and thereby move said jaws away from said faces, springs adapted to move said jaws toward said faces, and means adapted to successively assemble boxes with the labels carried by the second series.
46. In an apparatus of the character described, in combination, an intermittently rotatable support, a series of carriers movably connected thereto, a label magazine, means adapted to apply glue to said carriers, means adapted to reciprocate said carriers relatively to said support in line with the labels of the magazine when the support is at rest, whereby labels become adhesively attached to said respective carriers, a second intermittently rotatable series of carriers rotatable synchronously with the first series, each of said second carriers having a relatively movable face portion and oppositely disposed folding devices, means adapted to successively reciprocate the carriers of the first series relatively to those of the second and transfer the labels to the second carriers to position opposite the movable face portion, and means adapted to successively move boxes against said labels and with said movable portion relatively to said folding devices, thereby folding the labels on the boxes.
47. In an apparatus of the character described, in combination, an intermittently rotatable support, a series of carriers movably connected thereto, a label magazine, means adapted to apply glue to said carriers, means adapted to reciprocate said carriers relatively to said support in line with the labels of the magazine when the support is at rest, whereby labels become adhesively attached to said respective carriers, a second intermittently rotatable series of carriers rotatable synchronously with the first series, each carrier having a recess, a gripper jaw movable in said recess, and oppositely disposed folding devices, means adapted to successively reciprocate the carriers of the first series relatively to those of the second and transfer the labels to the second carriers opposite said gripper jaw, and means adapted to successively move boxes against said labels and with said jaw past said folding devices, thereby folding the labels on the boxes.
48. In an apparatus of the character described, in combination, an intermittently rotatable support, a series of carriers movably connected thereto, a label magazine, means adapted to apply glue to said carriers, means adapted to reciprocate said carriers relatively to said support in line with the labels of the magazine when the support is at rest, whereby labels become adhesively attached to said respective carriers, a second intermittently rotatable series of carriers rotatable synchronously with the first series, each carrier of the second series having a recess, a gripper jaw movable in said recess,

and oppositely disposed folding devices, means adapted to successively reciprocate the carriers of the first series relatively to those of the second and transfer the labels to the second carriers opposite said gripper jaw, means adapted to successively move boxes against said labels and with said jaw past said folding devices, thereby folding the labels on the boxes, and means adapted to yieldingly restrain movement of said gripper jaw.

49. In an apparatus of the character described, in combination, a label supply device, an intermittently rotatable support, a series of carriers movably connected to said support in oppositely disposed pairs, a fixed member having guides at oppositely disposed positions of rest in said rotary path in line with said supply device, carrier-engaging devices slideable on said guides, and means adapted to simultaneously reciprocate said carrier-engaging devices when engaged by said carriers.

50. In an apparatus of the character described, in combination, a label supply device, an intermittently rotatable support, a series of carriers movably connected to said support in oppositely disposed pairs, a fixed member having curved guides and oppositely disposed radial guides located at positions of rest in said rotary path in line with said label supply, carrier-engaging devices slideable on said radial guides and having guides adapted to align with said radial guides, and means adapted to simultaneously reciprocate said carrier-engaging devices when engaged by said carriers, comprising a rocker element concentric with said support, and links connecting said rocker element with said carrier-engaging devices.

51. In an apparatus of the character described, in combination, a label supply device, an intermittently rotatable support, a series of carriers movably connected to said support, means adapted to apply adhesive to said carriers, means adapted to move said carriers to and from said label supply device at a point of rest in the rotary path, whereby labels become adhesively attached to said carriers, means to remove the labels from the carriers comprising a centrally disposed reciprocating stripper on each carrier, and means to apply the stripped labels to articles.

52. In an apparatus of the character described, in combination, a label support comprising a movable plunger, folding devices disposed on opposite sides of said plunger, means adapted to hold a label on said support opposite said plunger, a reciprocating box carrier adapted when moved in one direction to press a box carried thereby against said label and with said label and plunger between said folding devices, and

means adapted to prevent the box following the movement of the box carrier in the opposite direction.

53. In an apparatus of the character described, in combination, a label support comprising relatively stationary portions, a movable plunger intermediate said portions, folding devices disposed on opposite sides of said plunger, means adapted to hold a label on said support opposite said plunger comprising reciprocating jaws adapted to clamp the label against said stationary portions, jaws adapted to yieldingly grip a box, a reciprocating rod supporting said jaws, a reciprocating box detainer, means adapted to move said supporting rod to press a box carried by said jaws against said label and said box, label and plunger between said folding devices, and means to cause said detainer to remain at rest for a portion of the return movement of said jaws.

54. In an apparatus of the character described, in combination, a label support comprising relatively stationary portions, a movable plunger intermediate said portions, folding devices disposed on opposite sides of said plunger, means adapted to hold a label on said support opposite said plunger comprising reciprocating jaws adapted to clamp the label against said stationary portions, jaws adapted to yieldingly grip a box, a reciprocating rod supporting said jaws, a reciprocating box detainer comprising a rod concentric with said supporting rod, means adapted to simultaneously move said rods and press a box carried by said jaws against said label and said box, label and plunger between said folding devices, and a pawl adapted to prevent movement of said detainer rod in the opposite direction, said supporting rod adapted, at a predetermined point in its retreating path, to cause said pawl to free said detainer rod.

55. In an apparatus of the character described, in combination, a box magazine, means adapted to cause boxes to move therein to predetermined position, a box carrier spaced from said magazine and comprising yielding box-gripping jaws, means to reciprocate said carrier in a plane parallel to that of the boxes in the magazine, and means adapted to slide boxes one by one from said magazine to between said jaws.

56. In an apparatus of the character described, in combination, a box magazine, means adapted to cause boxes to move therein to predetermined position, a box carrier spaced from said magazine and comprising yielding box-gripping jaws, means to reciprocate said carrier in a plane parallel to that of the boxes in the magazine, a reciprocating box-pushing head adapted to slide boxes one by one from the magazine to between said jaws, a rod connected to

said head, a rock shaft, an arm on said shaft pivotally connected to said rod, a gear on said shaft, a rack engaging said gear, and means to reciprocate said rack.

5 57. In an apparatus of the character described, in combination, a box magazine, means adapted to cause boxes to move therein to predetermined position, a box carrier spaced from said magazine and comprising 10 yielding box-gripping jaws having curved gripping faces, means to reciprocate said carrier in a plane parallel to that of the boxes in the magazine, and means adapted to slide boxes one by one from said magazine to between said jaws.

15 58. In an apparatus of the character described, in combination, a series of label carriers, means on said carriers adapted to grip labels thereto, means adapted to move said 20 carriers to a predetermined position, said carriers comprising relatively movable label-folding faces, and a reciprocatory box carrier adapted to successively move boxes against labels on said label carriers opposite 25 said faces.

30 59. In an apparatus of the character described, in combination, a series of label carriers, means on said carriers adapted to grip labels thereto, means adapted to move said carriers to a predetermined position, said carriers comprising spaced label-folding devices intermediate the ends 35 of the labels, and a reciprocatory box carrier adapted to successively move boxes against labels on said label carriers and the labels and boxes relatively to said folding devices.

40 60. In an apparatus of the character described, in combination, a series of label carriers, means adapted to move said carriers to a predetermined position, said carriers comprising label-folding devices, means adapted to restrain curling of said labels, and a reciprocatory box carrier adapted 45 to successively move boxes against labels on said label carrier and the labels and boxes relatively to said folding devices.

50 61. In an apparatus of the character described, in combination, a series of label carriers, means adapted to move said carriers to a predetermined position, said carriers comprising devices to grip labels thereto and relatively movable label-folding faces, and a reciprocatory box carrier 55 adapted to successively move boxes against labels on said carriers opposite said label-folding faces.

60 62. In an apparatus of the character described, in combination, a series of label carriers, means adapted to move said carriers to a predetermined position, said carriers comprising devices adapted to grip labels thereto, label-folding devices and relatively movable label-folding faces, and a reciproc-

65 atory box carrier adapted to successively move boxes against labels on said carriers opposite said faces, and said boxes, labels and faces relatively to said folding devices.

70 63. In an apparatus of the character described, in combination, a series of label carriers, means adapted to move said carriers to a predetermined position, said carriers comprising devices adapted to grip labels thereto, label-folding devices and relatively movable label-folding faces, a reciprocatory box carrier adapted to successively move boxes against labels on said carriers opposite said faces, and said boxes, labels and faces relatively to said folding devices, 75 and means adapted to restrain curling of portions of said labels.

80 64. In an apparatus of the character described, in combination, a series of label carriers, means adapted to move said carriers to a predetermined position, said carriers comprising jaws adapted to grip labels thereto, a reciprocatory box carrier adapted to move successive boxes against said labels on said label carriers while gripped by said jaws, and means to release the grip of said jaws upon contact of said labels and boxes.

85 65. In an apparatus of the character described, in combination, a series of label carriers, means adapted to move said carriers to a predetermined position, said carriers comprising recessed portions, and reciprocatory jaws adapted to enter said recesses and grip labels to said carriers thereby tensioning the labels on the carriers.

90 66. In an apparatus of the character described, in combination, a series of label carriers, means adapted to move said carriers to a predetermined position, said carriers comprising recessed portions, and reciprocatory beveled jaws adapted to enter said recesses and grip labels to said carriers.

95 67. In an apparatus of the character described, in combination, a series of label carriers, means adapted to hold labels thereon, means adapted to move said carriers to a predetermined position, said carriers comprising a relatively reciprocatory box-gripping jaw and label-folding devices, and a reciprocatory box carrier adapted to successively move boxes against labels on said label carriers opposite said box-gripping jaw and with said jaw relatively to said label-folding devices.

100 68. In an apparatus of the character described, in combination, a series of label carriers, means adapted to hold labels thereon, means adapted to move said carriers to a predetermined position, said carriers comprising a relatively reciprocatory box-gripping jaw and label-folding devices, means adapted to yieldingly resist said relative movement of said jaw, and a reciprocatory box carrier adapted to successively move

boxes against labels on said label carriers opposite said box-gripping jaw and with said jaw relatively to said label-folding devices.

5. 69. In an apparatus of the character described, in combination, a series of label carriers, means adapted to hold labels thereon, means adapted to move said carriers to a predetermined position, said carriers comprising a relatively reciprocatory box-gripping jaw and oppositely disposed rigid portions, brushes spaced apart intermediate said rigid portions, and a reciprocatory box carrier adapted to successively move boxes 10 against labels on said label carriers opposite said box-gripping jaw and with said jaw relatively to said brushes.

70. In an apparatus of the character described, in combination, a series of label carriers, means adapted to move said carriers to a predetermined position, said carriers comprising a relatively reciprocatory box-gripping jaw and oppositely disposed rigid portions, brushes spaced apart intermediate 20 said rigid portions, reciprocatory label-gripping jaws adapted to coöperate with said rigid portions, and a reciprocatory box carrier adapted to successively move boxes against labels on said label carriers opposite 25 said box-gripping jaw and with said jaw relatively to said brushes.

71. In an apparatus of the character described, in combination, a rotatable series of label carriers, means adapted to intermittently rotate said series, reciprocatory gripper jaws adapted to coöperate with said carriers to hold and release labels on the carriers, a reciprocatory article carrier adapted to successively move articles against the 30 labels on the label carriers when the label carriers are in predetermined position, means adapted to deliver labels to said label carriers before said predetermined position is attained and cause said jaws to retain the 35 same thereon, and means to cause said jaws to release said labels, upon contact of the articles therewith.

72. In an apparatus of the character described, in combination, a rotatable series 50 of label carriers, means adapted to intermittently rotate said series, reciprocatory gripper jaws for each carrier movable to and from the same, a box carrier adapted to move to and from the label carriers when 55 the latter are in a predetermined position of rest, means to supply boxes successively to said box carrier, and means comprising an oscillatory cam adapted to move said jaws to and from the label carriers at predetermined intervals.

73. In an apparatus of the character described, in combination, a rotatable series of label carriers, means adapted to intermittently rotate said series, slidably mounted

reciprocatory gripper jaws for each carrier 65 movable to and from the same, a box carrier adapted to move to and from the label carriers when the latter are in a predetermined position of rest, means to supply boxes successively to said box carrier, and means comprising an oscillatory cam and rock levers 70 operatively connected to said jaws and cam adapted to move said jaws to and from the label carriers at predetermined intervals.

74. In an apparatus of the character described, in combination, a rotatable series of label carriers, means adapted to intermittently rotate said series, each carrier comprising a relatively movable label pressing plunger, means adapted to deliver a label to 80 each carrier before a predetermined position is attained, and a reciprocatory box carrier adapted to successively move boxes against labels on said label carriers opposite said plunger when said label carriers are in 85 said predetermined position.

75. In an apparatus of the character described, in combination, a rotatable series of label carriers, means adapted to intermittently rotate said series, a cam, each carrier comprising a relatively movable label pressing plunger guided by said cam, means 90 adapted to deliver a label to each carrier before a predetermined position is attained, and a reciprocatory box carrier adapted to 95 successively move boxes against labels on said label carriers opposite said plunger when said label carriers are in said predetermined position.

76. In an apparatus of the character described, in combination, a rotatable series of label carriers, means adapted to intermittently rotate said series, a fixed cam, each carrier comprising a relatively movable label pressing plunger guided by said cam, means 100 adapted to deliver a label to each carrier before a predetermined position is attained, and a reciprocatory box carrier adapted to 105 successively move boxes against labels on said label carriers opposite said plunger when said label carriers are in said predetermined position.

77. In an apparatus of the character described, in combination, a rotatable series of label carriers, means adapted to intermittently rotate said series, a fixed cam, each carrier comprising rigid label supporting portions and an intermediate relatively 115 movable plunger portion, means adapted to deliver a label to each carrier before a predetermined position is attained, and a reciprocatory box carrier adapted to successively move boxes against labels on said label carriers opposite said plunger when said label carriers are in 120 said predetermined position.

78. In an apparatus of the character described, in combination, a rotatable series of label carriers, each comprising relatively

- stationary label supporting portions and an intermediate relatively movable plunger portion, means adapted to intermittently rotate said series, a fixed cam comprising an end-
5 less track, said plunger portions comprising parts guided in said track, means adapted to frictionally restrain said relative movement of said plungers, means adapted to deliver a label to each of said carriers before a predetermined position is attained,
10 and a reciprocatory box carrier adapted to successively move boxes against labels on said label carriers opposite said plunger when said label carriers are in said predetermined position.
79. In an apparatus of the character described, in combination, a rotatable series of label carriers, each carrier comprising relatively stationary label supporting portions, intermediate label folding portions and a relatively transversely movable plunger intermediate said label folding portions, reciprocatory gripper jaws adapted to co-operate with said stationary supporting portions to hold and release labels on said carriers, means adapted to deliver labels to said carriers before a predetermined position is attained, a reciprocatory box carrier adapted to successively move boxes against labels on said label carriers opposite said plungers and with said plungers relatively to said folding portions when said label carriers are in said predetermined position, and means to cause said jaws to release said labels to permit them to move with said boxes.
80. In an apparatus of the character described, in combination, a rotatable series of label carriers, each carrier comprising relatively stationary label supporting portions, intermediate label folding portions and a relatively transversely movable plunger intermediate said label folding portions, reciprocatory gripper jaws adapted to co-operate with said stationary supporting portions to hold and release labels on said carriers, means adapted to deliver labels to said carriers before a predetermined position is attained, a reciprocatory box carrier adapted to successively move boxes against labels on said label carriers opposite said plungers and with said plungers relatively to said folding portions when said label carriers are in said predetermined position, and means comprising an oscillatory cam and connections between said cam and said jaws adapted to operate the latter.
81. In an apparatus of the character described, in combination, a rotatable series of label carriers, each carrier comprising relatively stationary label supporting portions, intermediate label folding portions and a relatively transversely movable plunger intermediate said label folding portions, reciprocatory gripper jaws adapted to co-operate with said stationary supporting portions to hold and release labels on said carriers before a predetermined position is attained, a reciprocatory box carrier adapted to successively move boxes against labels on said label carriers opposite said plungers and with said plungers relatively to said folding portions when said label carriers are in said predetermined position, and means comprising an oscillatory cam and connections between said cam and said jaws adapted to operate the latter.
82. In an apparatus of the character described, in combination, means adapted to attach a flexible strip around a sectional box across the joint, and means adapted to sever said strip in line with said joint.
83. In an apparatus of the character described, in combination, means adapted to adhesively attach a flexible strip around a sectional box across the joint, and means adapted to sever said strip in line with said joint on one side.
84. In an apparatus of the character described, in combination, a labeling mechanism, a slitting mechanism, means adapted to cause said labeling mechanism to successively fold labels around sectional boxes across their joints and adhesively attach the same thereto, means adapted to successively transfer said labeled boxes to said slitting mechanism, and means to cause said slitting mechanism to sever said attached labels in line with the joint at one side of said boxes.
85. In an apparatus of the character described, in combination, a set of rotatable carriers, a second set of rotatable carriers mounted on a different axis from the first set, the carriers of said second set comprising article-holding means, and means adapted to cause labels carried by said first set to be transferred to said second set and thereafter adhesively assembled with articles on said second set.
86. In an apparatus of the character described, in combination, a set of rotatable carriers, a second set of rotatable carriers mounted on a different axis from the first set, the carriers of said second set comprising article-holding means, and means adapted to cause labels carried by said first set to be transferred to said second set and thereafter adhesively assembled with articles on said second set, said second set comprising means adapted to remove the assembled labels and articles therefrom.
87. In an apparatus of the character described, in combination, a set of rotatable carriers, a second set of rotatable carriers, mounted on a different axis from the first

set, the carriers of said second set comprising article-holding means and label-folding devices, and means adapted to cause labels carried by said first set to be transferred to 5 said second set and folded on articles held by said second set.

88. In an apparatus of the character described, in combination, an intermittently rotatable carrier, a label supply device, 10 means adapted to cause a label of the supply to be adhesively attached to said carrier, a second intermittently rotatable carrier comprising an article holder, means adapted to transfer said label from the first-men- 15 tioned carrier to the second carrier and interpose the material of the label between the adhesive face thereof and said second carrier, and means adapted to assemble the label on the second carrier with an article in 20 said holder.

89. In an apparatus of the character described, in combination, an intermittently rotatable carrier, a stationary label supply device, means adapted to cause a label of 25 the supply to be adhesively attached to said carrier, a second intermittently rotatable carrier comprising an article holder, means adapted to transfer said label from the first-mentioned carrier to the second carrier and 30 interpose the material of the label between the adhesive face thereof and said second carrier, and means adapted to assemble the label on the second carrier with an article.

90. In an apparatus of the character described, in combination, an intermittently rotatable carrier, a label supply device, means adapted to cause a label of the supply to be adhesively attached to said carrier, a second intermittently rotatable carrier, 35 means adapted to transfer said label from the first-mentioned carrier to the second carrier and interpose the material of the label between the adhesive face thereof and said second carrier, and means adapted to assemble 40 the label on the second carrier with an article at a point of rest in the path of said second carrier.

91. In an apparatus of the character described, in combination, an intermittently 50 rotatable carrier providing a generally plane label-supporting face in its rotary plane, a label supply device, means adapted to cause a label of the supply to be adhesively attached to said face of said carrier, a second intermittently rotatable carrier providing a 55 generally plane label-supporting face in its rotary plane, means adapted to transfer said label from the first-mentioned carrier to the second carrier and interpose the ma- 60 terial of the label between the adhesive face thereof and said second carrier, and means adapted to assemble the label on the second carrier with an article.

92. In an apparatus of the character described, in combination, an intermittently 65 rotatable carrier, a stationary label supply device, means adapted to cause a label of the supply to be adhesively attached to said carrier, a second intermittently rotatable carrier comprising an article holder, means 70 adapted to transfer said label from the first-mentioned carrier to the second carrier and interpose the material of the label between the adhesive face thereof and said second carrier, and means adapted to as- 75 semble the label with an article on the second carrier in said holder.

93. In an apparatus of the character described, in combination, an intermittently rotatable carrier, a label supply device, 80 means adapted to move said carrier at an angle to its rotary path and cause a label of the supply to be adhesively attached thereto, a second intermittently rotatable carrier comprising an article holder, means 85 adapted to transfer said label from the first-mentioned carrier to the second carrier by a movement of said first-mentioned carrier at an angle to its rotary path and interpose the material of the label between 90 the adhesive face thereof and said second carrier, and means adapted to assemble the label with an article on the second carrier in said holder.

94. In an apparatus of the character described, in combination, an intermittently rotatable carrier, a stationary label supply device, means adapted to move said carrier at an angle to its rotary path and cause a label of the supply to be adhesively attached thereto, a second intermittently rotatable carrier comprising an article holder, means adapted to transfer said label from the first-mentioned carrier to the second carrier by a movement of said 100 first-mentioned carrier at an angle to its rotary path and interpose the material of the label between the adhesive face thereof and said second carrier, and means adapted to assemble the label with an article on the 105 second carrier in said holder.

95. In an apparatus of the character described, in combination, an intermittently rotatable carrier, a stationary label supply device, means adapted to cause a label of the 115 supply to be adhesively attached to said carrier, a second intermittently rotatable carrier comprising an article holder, means adapted to transfer said label from the first-mentioned carrier to the second carrier 120 and interpose the material of the label between the adhesive face thereof and said second carrier, and means adapted to assemble the label with an article on the second carrier in said holder at a point of rest in 125 the path of said second carrier.

96. In an apparatus of the character described, in combination, an intermittently rotatable carrier, a stationary label supply device, means adapted to move said carrier at an angle to its rotary path and cause a label of the supply to be adhesively attached thereto, a second intermittently rotatable carrier comprising an article holder, means adapted to transfer said label from the first-mentioned carrier to the second carrier by a movement of said first-mentioned carrier at an angle to its rotary path and interpose the material of the label between the adhesive face thereof and said second carrier; and means adapted to assemble the label with an article on the second carrier in said holder at a point of rest in the path of said second carrier.

97. In an apparatus of the character described, in combination, an intermittently rotatable carrier, a stationary label supply device, means adapted to move said carrier at an angle to its rotary path and cause a label of the supply to be adhesively attached thereto, a second intermittently rotatable carrier, means adapted to transfer said label from the first-mentioned carrier to the second carrier and interpose the material of the label between the adhesive face thereof and said second carrier, and means adapted to assemble the label on the second carrier with an article.

98. In an apparatus of the character described, in combination, an intermittently rotatable carrier, a stationary label supply device, means adapted to move said carrier at an angle to its rotary path and cause a label of the supply to be adhesively attached thereto, a second intermittently rotatable carrier, means adapted to transfer said label from the first-mentioned carrier to the second carrier and interpose the material of the label between the adhesive face thereof and said second carrier, and means adapted to assemble the label on the second carrier with an article at a point of rest in the path of said second carrier.

99. In an apparatus of the character described, in combination, mechanism adapted to automatically attach a label across a joint of a sectional box, label slitting mechanism, and means adapted to automatically feed labeled boxes from said attaching mechanism into cooperative relation with said slitting mechanism.

100. In an apparatus of the character described, in combination, mechanism adapted to automatically attach a label across a joint of a sectional box, label slitting mechanism, a press, and means adapted to automatically feed labeled boxes from said attaching mechanism through said press into cooperative relation with said slitting mechanism.

101. A carrier plate having a flat label carrying face, means adapted to move said plate in an endless path, means adapted to coat the flat face of said plate with adhesive, a label supply device fixed opposite a predetermined point of the path of said plate, means adapted to effect relative approaching movement between said plate and a label on the supply device to cause said label to adhere to said coated face, a rotatable carrier adjacent the path of movement of said plate, means adapted to transfer the label from said plate to said carrier and interpose the material of said label between the adhesive face thereof and said carrier comprising a label gripping finger mounted on said carrier and adapted to grip a part of said label to said carrier while said label is on said plate, and means adapted to apply said coated label to an article.

102. A carrier plate having a flat label carrying face, means adapted to move said plate in an endless path, means adapted to coat the flat face of said plate with adhesive, a label supply device fixed opposite a predetermined point of the path of said plate, means adapted to effect relative approaching movement between said plate and a label on the supply device to cause said label to adhere to said coated face, a rotatable carrier adjacent the path of movement of said plate, means adapted to transfer the label from said plate to said carrier and interpose the material of said label between the adhesive face thereof and said carrier comprising a label gripping finger mounted on said carrier and adapted to grip a part of said label to said carrier while said label is on said plate, and means adapted to apply said coated label to an article.

103. In an apparatus of the character described, in combination, a label carrier, means adapted to rotate said carrier, said carrier comprising fingers adapted to grip a label thereto, a reciprocatory member adapted to move a box against said label on said carrier while gripped by said fingers, and means to release the grip of said fingers.

104. In an apparatus of the character described, in combination, a label carrying plate, means adapted to move said plate in an endless path, means adapted to coat a face of said plate with adhesive, a label supply device, means adapted to effect relative approaching movement between said plate and a label on the supply device to cause said label to adhere to said coated face, a rotatable label carrier adjacent the path of movement of said plate, means adapted to transfer the label from said plate

to said carrier and interpose the material of
said label between the adhesive face thereof
and said carrier, comprising a label gripping
finger mounted on said carrier adapted to
5 grip a part of said label to said carrier while
said label is on said plate, and means adapted
to apply said coated label to an article.

In testimony whereof I affix my signature,
in the presence of two witnesses.

ROBINSON BURT.

Witnesses:

R. E. Wood,
L. C. PALMER.

It is hereby certified that in Letters Patent No. 1,180,005, granted April 18, 1916, upon the application of Robinson Burt, of Buffalo, New York, for an improvement in "Labeling-Machines," errors appear in the printed specification requiring correction as follows: Page 8, line 36, for the reference-numeral "268" read 263; page 11, line 96, claim 9, for the word "carried" read *carrier*; and that the said Letters Patent should be read with these corrections therein that the same may conform to the record of the case in the Patent Office.

Signed and sealed this 30th day of May, A. D., 1916.

[SEAL.]

J. T. NEWTON,

Acting Commissioner of Patents.
